(57) **CLAIM**

The ornamental design for a split shoulder strap, as shown and described.

DESCRIPTION

FIG. 1 is a top plan view of the split shoulder strap showing my new design, the bottom view being a mirror image thereof;

FIG. 2 is a side elevation view the split shoulder strap, the opposite side being a mirror image thereof;

FIG. 3 is a first end view plan view of the split shoulder strap;

FIG. 4 is a second end view plan view of the split shoulder strap; and,

FIG. 5 is a cross-sectional view taken along line 5-5 in FIG. 1.

The broken line showing environment in the Figures is for illustrative purposes only and forms no part of the claimed design.
